Assistant Examiner — Natasha Vujcic(74) *Attorney, Agent, or Firm* — Jackson Walker L.L.P.(57) **CLAIM**

The ornamental design for a vehicle step, as shown and described.

DESCRIPTION

FIG. 1 is a perspective view of a vehicle step illustrating the design.

FIG. 2 is a side view of the vehicle step of FIG. 1.

FIG. 3 is an opposite side view of the vehicle step of FIG. 1.

FIG. 4 is a front view of the vehicle step of FIG. 1.

FIG. 5 is a rear view of the vehicle step of FIG. 1.

FIG. 6 is a top view the vehicle step of FIG. 1.

FIG. 7 is bottom view of the vehicle step of FIG. 1.

FIG. 8 is a perspective view of a vehicle step similar to that in FIG. 1 in use on a pick-up truck; and,

FIG. 9 is a perspective view of a second embodiment of a vehicle step. Except for the break lines, the second embodiment is the same in appearance as the first embodiment.

The broken lines in the figures, which show a vehicle, represent the environment for use. The broken lines form no part of the claimed design. The break lines in FIG. 9 indicate that the appearance of any portion of the vehicle step between the break lines forms no part of the claimed design.
